UNITED STATES PATENT OFFICE.

WALTER H. HANNA, OF BENTON HARBOR, MICHIGAN, ASSIGNOR, BY MESNE ASSIGNMENTS, TO BAKER-VAWTER COMPANY, OF BENTON HARBOR, MICHIGAN, A CORPORATION OF MICHIGAN.

ACCOUNT-TRAY.

1,272,699.

Specification of Letters Patent. Patented July 16, 1918.

Application filed March 6, 1916. Serial No. 82,297.

To all whom it may concern:

Be it known that I, WALTER H. HANNA, a citizen of the United States, residing at Benton Harbor, in the county of Berrien and 5 State of Michigan, have invented certain new and useful Improvements in Account-Trays, of which the following is a specification.

My invention relates to a posting or account tray or box which is designed to hold 10 a variable number of sheets containing accounts, and is so designed as to be particularly useful in connection with adding and registering machines which are adapted to 15 be used to post items on the sheets and mechanically add together the amounts of different items so entered. It has heretofore been a common practice to keep such account sheets in a loose leaf binder or similar account book, and when new items are to be 20 entered, transfer in a block all the sheets to a posting box designed to facilitate handling, and when the posting and bookkeeping operations are completed replace them in the 25 binder. My present posting tray is intended to provide in one article a substitute for the binder and the posting tray, or rather it may be considered as itself constituting an account book of unusual capacity and adapted 30 to permit the use of the sheets in the same manner as in a posting tray. With this and incidental objects and advantages in view, my invention consists in a structure of the character indicated, and having the construction 35 and arrangement of parts hereinafter described, the essential elements of the same being more particularly pointed out in the appended claims.

In the drawings Figure 1 is a side view of 40 my improved posting box with the ledger sheets pressed lightly together in closed-up position and the cover of the box on; Fig. 2 is a vertical cross-section on the line 2—2 of Fig. 1; Fig. 3 is a top plan view of the box 45 without the cover with the leaves and movable parts in the same position as in Fig. 1; Fig. 4 is a longitudinal vertical section, on the line 4—4 of Fig. 3, but with the movable parts and leaves opened out into working 50 position; Fig. 5 shows the lower portion of a modified form of sheet, the right-hand side being partly broken away; and Fig. 6 is

a detail showing the matter in which the front end of the spacing rod is secured in place.

The same letters of reference indicate the same parts in the different views.

The body 1 of my improved box is preferably constructed of sheet metal, and is provided with handles for convenient handling, 60 and felt disk feet to rest upon. Adjacent the sides of the box inner walls 3—3 of slightly less height than such sides are arranged and rigidly secured in place by suitable means, as by the integral flanges 3^a, 3^a riveted to the 65 body of the box. Extending across and sliding upon the top edges of the inner walls 3—3 is a follower bar 4, having a vertical depending portion 4^a and equipped with a suitable gripping mechanism engaging such 70 walls. While the specific construction of the follower grip mechanism constitutes no part of my present invention, it may be here stated that in the device shown a pair of pivoted wedging members 5 are engaged and 75 arranged to be oscillated through a pair of spring-pressed links 6 which extend toward the center line of the box, and near their meeting ends are bent upwardly through slots in the bar 4 and are arranged and 80 adapted to be pinched toward each other between the thumb and forefinger so as to cause disengagement of the wedging members and permit the follower to be slid freely back and forth. A loosely fitting 85 metal plate 7 is provided which may be inclined against the follower at any angle desired and serves as the back support for the account sheets and index leaves. Near the front end of the box a similar plate 8 is 90 hinged by a hinge-plate 8^a to the bottom of the box, this plate being adapted, when in the inclined position shown in Fig. 4, to serve as a rest for such leaves as have been thrown forwardly, and when in the vertical 95 position shown in Figs. 1 and 3 to serve as a stop against which the ledger sheets may be compressed by the action of the follower and plate 7 upon the opposite side of such sheets, the vertical portion 4 of the follower at this 100 time tending to force the plate 7 into vertical position parallel to the plate 8. To hold the plate 8 in its two different positions I have provided the stop plate 9, strengthened by

the side bracket members or flanges 10 and front roll or bead 11, and which is hinged to the front of the box and arranged either to lie in the position shown in Fig. 1 (in which 5 the flanges 10 serve as brackets to support it), or in the position shown in Fig. 4, for the purpose stated.

The account sheets for which my improved posting box is designed are narrower than the space between the sides of 10 the box, to enable part of the sheets to be offset with respect to the remaining sheets. In the box illustrated the arrangement is such that in the course of using the tray 15 in the manner in which it is designed to be used, part of the sheets are one by one offset from the main body of sheets arranged with their left-hand edges adjacent the left-hand wall 3 to a position in which their right- 20 hand edges lie adjacent the right-hand wall. In order to adapt all the sheets to be readily placed and positively retained in either position, the sheets are in the present instance slotted or notched at two places on their 25 bottom edges and a spacing rod 12 provided to coöperate with one or the other of these notches, the arrangement being such as to produce the relative displacement desired. Preferably this rod is made adjustable to 30 different positions, so that a narrower leaf can be operated just as well as a wider leaf, thus permitting one box to accommodate various widths of leaves. To this end, the rod 12 is in the present instance mounted in 35 one or the other of two pairs of front and rear holes in the vertical members of an angle-plate 13 secured on top of the hinge plate 8^a to the bottom of the box near the front, and an angle-plate 13^a near the rear 40 thereof, the front end of the rod being equipped with a knurled post 14 having a screw-threaded lower end adapted to engage one or the other of a corresponding number of screw-sockets in the angle-plate 45 13 at the bottom of the box, see Fig. 6, also Fig. 3. It will be understood, however, that three or more notches may be provided at the bottom of the sheet, as in the modified form of sheet illustrated in Fig. 5, and the 50 main body of sheets placed in an intermediate position, so that the sheets may be offset either to the right or left, if desired or necessary to the intended use of the sheets being employed; and also that other 55 arrangements of rods and notches, as the use of two rods with one or more notches, or the provision of additional adjusting holes in the angle-plate 13, and additional notches in the account sheets are practicable 60 to permit the sheets to be offset in any manner desired.

A sheet of canvas 15, or other suitable material, is secured to the bottom of the box, as by means of the angle-plate 13 and hinge-plate 8^a, in order to furnish a frictional sur-

face for the account sheets to rest upon, and thus prevent them from slipping and crowding forward at the bottom when they are spread open for work. It will be noted that the front plate 8 is only adjustable 70 angularly, but the rear plate 7 may not only be set to any desired angle but may be shifted forwardly and rearwardly, whereby the box is adapted to receive any number of sheets within its structural limits. 75

The cover 16 of the box is arranged to interlock with the body 1 through the engagement of a projection 17 on the rear wall of the latter with a corresponding recess in the cover, and the cover is equipped with a lock 18, the laterally spreading bolts of which coöperate with a keeper 19 secured to the front wall of the body 1. It will be seen by reference to Figs. 3 and 4 of the drawings that the central part of the 85 plate 8 is cut out to avoid interference with this keeper.

It will be understood that when not in use the plates 7 and 8 are in vertical position and pressed as tightly together as practicable, in which position they will be retained by the grip of the follower mechanism, in order to keep the ledger sheets and index sheets flat and smooth. When posting is to be done the follower is adjusted 95 rearwardly a proper distance to cause the sheets to incline at a convenient angle, and the plate 9 elevated and the plate 8 tilted to forward position.

After the posting and balancing of the 100 accounts for one period has been completed, and before beginning the posting for a new period, all the leaves previously displaced will have been returned to the left-hand side of the box. Then, as the posting proceeds, 105 the leaves upon which entries are to be made are taken out and put in the posting machine (assuming that one is being used), and an entry made upon it and the sheet replaced in off-set position, the cut-out slots 110 at the bottom of the leaves positively maintaining the sheets in position. However, it is obvious that if desired the rod can be removed and the box used without it in a similar manner, though without the advantage of positive retention of the sheets 115 in their different positions. The new entries are thus all found upon the sheets which are displaced to right-hand position, in position for use in making and checking up 120 a balance, and this having been made the sheets are returned to right-hand position for a new posting.

I claim:

1. A posting box of the character described and comprising the box proper, a hinged front plate, means for supporting said front plate is tilted and in vertical position, a detached rear plate, and an adjustable follower supporting said rear plate at 130

the back of its upper portion whereby such rear plate may be set forwardly or rearwardly and tilted as desired.

2. A posting box of the character described and comprising the box proper, a hinged front plate, a hinged stop plate which in two opposite positions coöperates with said front plate to hold it vertical in the one position and tilted in the other, and 10 a rear plate which is adjustable from front to rear and angularly adjustable.

3. A posting box of the character described and comprising the box proper, a hinged front plate, a hinged stop plate 15 which in two opposite positions coöperates with said front plate to hold it vertical in the one position and tilted in the other, said stop plate being formed with a depending bracket member, and a rear plate 20 which is adjustable from front to rear and angularly adjustable.

4. A posting box of the character described and comprising the box proper, a hinged front plate, a hinged stop plate 25 which in two opposite positions coöperates with said front plate to hold it vertical in the one position and tilted in the other, said stop plate being arranged to contact the side of the box to limit its movement in one direction and being formed with a depending flange arranged to also contact the side of the box to limit its movement in the other direction, and a rear plate which is adjustable from front to rear and angularly 30 adjustable.

5. A posting box of the character described and comprising the box proper, a hinged front plate, a hinged stop plate which in two opposite positions coöperates 40 with said front plate to hold it vertical in the one position and tilted in the other, said stop plate being formed with a bead at its front edge and depending side flanges constituting bracket members, and a rear plate 45 which is adjustable from front to rear and angularly adjustable.

6. A posting box of the character described and comprising the box proper, an angularly adjustable front plate, a loose 50 rear plate, and an adjustable follower supporting said rear plate and having a broad extended vertical portion.

7. In a device of the character described and in combination with leaves formed with 55 a pair of open slots in their bottom edges, a box wider than the cards, front and rear plates adapted to support said cards in inclined positions, front and rear angle-plates secured to the bottom of the box and

having similar sets of holes formed in their vertical members, a rod arranged to engage corresponding front and rear holes in said two angle-plates, and securing means at the front of the rod for holding it in set position.

8. In a device of the character described and in combination with leaves formed with a pair of open slots in their bottom edges, a box wider than the cards, front and rear plates adapted to support said cards in inclined position, front and rear angle plates having their horizontal members secured to the bottom of the box and having similar sets of holes formed in their vertical members, a rod arranged to engage corresponding front and rear holes in said two angle-plates, and a sheet of fabric upon the bottom of the box between said angle-plate extending under the horizontal members of such plates and held in place thereby.

9. In a box of the character described and in combination with a set of sheets adapted to be held therein upon their edges, a front plate arranged to be set to vertical position and also to tilted position, a rear plate, and a follower adapted to coöperate with said rear plate to hold it in tilted position and having a vertical face adapted to force said plate into vertical position when said front plate is vertical and said follower is moved to press said rear plate against the interposed sheets.

10. A file box comprising a receptacle for the sheets to be filed, a pair of tiltable back members arranged in said receptacle, said tiltable back members being so arranged that the filed sheets will be confined between them, a hinge securing the lower edge of one of said tiltable back members to said receptacle, the other tiltable back member being adjustable to different positions to compensate for variations in the dimensions of the body of filed sheets, and an adjustable follower fitted to the last mentioned back member.

11. A file box comprising a receptacle for the sheets to be filed, a tiltable back member arranged to form an inclined supporting element for the filed sheets, a filler associated with said tiltable back member, and a pivot supporting said filler, said filler being adapted to retain the tiltable back member in a substantially vertical position.

WALTER H. HANNA.
